UNITED STATES PATENT OFFICE.

THEODORE ABTMAYER, OF WILKINSBURG, PENNSYLVANIA, ASSIGNOR TO WESTINGHOUSE ELECTRIC AND MANUFACTURING COMPANY, A CORPORATION OF PENNSYLVANIA.

INTERRUPTER.

1,171,576.

Specification of Letters Patent.

Patented Feb. 15, 1916.

Application filed August 11, 1913. Serial No. 784,090.

To all whom it may concern:

Be it known that I, THEODORE ABTMAYER, a citizen of the United States, and a resident of Wilkinsburg, in the county of Allegheny and State of Pennsylvania, have invented a new and useful Improvement in Interrupters, of which the following is a specification.

My invention relates to interrupters for use in connection with the ignition systems of internal combustion engines, and it has for its object to provide a device which operates with a uniformly quick movement at varying engine speeds.

In the accompanying drawings, Figure 1 is a side and sectional view of a combined spark advancer and interrupter constructed in accordance with my invention. Fig. 2 is an end and sectional view of the mechanism of Fig. 1. Fig. 3 is a view, similar to Fig. 2, of a modification.

My invention is adapted to be employed in connection with a magneto or generator, or it may be connected directly to the engine. The mechanism is mounted upon a shaft 1 which may be a part of any of said machines. Two pins or posts 2 and 3 are screwed into holes in the end of the shaft 1 at opposite sides of its axis and parallel thereto to serve as pivots for two centrifugally actuated levers 4 and 5 of substantially semi-cylindrical outer contour and having central shallow channels in their circumferential faces which form ribs adjacent to their edges. The abutting faces 4^a and 5^a of the ends of levers 4 and 5 are radial for approximately one-fourth of the diameters of their cylindrical portions and the remaining or inner portions of the abutting faces are of irregular contour, being severally shaped to provide laterally extending arms 6 and 7 and recesses 8 and 9 for the reception of the opposing arms. The engaging faces of the arms and recesses are of such shape that the levers are caused to move simultaneously and correspondingly under the action of centrifugal force. Thus, movement of the lever 4 upon its pivot 2 causes the arm 6 to press against the face of the recess in the lever 5 to effect a corresponding movement of the said lever, and movement of the lever 5 upon its pivot 3 causes

the arm 7 to press against the face of the recess in the lever 4 to effect a corresponding movement of the said lever.

55

Diametrically opposite ends of the levers 4 and 5 are slotted for the reception of rollers 10 and 11 that protrude from the slots slightly beyond the cylindrical faces of the levers, the said rollers being mounted upon pins 10^a and 11^a that extend through the levers and project from the outer end faces thereof. The other ends of the levers 4 and 5 are solid and constitute weights upon which centrifugal forces act to move the levers, and the disposition of the rollers with respect to the pivot or fulcrum points of the levers is such that they are moved both angularly forward and radially outward as the weighted ends of the levers are moved outwardly by centrifugal force. In this connection, it will be noted that the cylindrical faces of the levers 4 and 5 are not concentric with the axes about which they revolve, thus permitting of movements of the levers with 75 in the limited space allowed.

The levers 4 and 5 are normally maintained in the positions shown by means of springs 12 that are supported by arms 13 carried by a block 14 that is mounted upon 80 the outer ends of the pins or posts 2 and 3, the said block being secured upon said pins by means of a cotter pin 15 that extends through transverse apertures in the ends of the pins. The free ends of the springs 12 85 bear against the inner faces of the projecting ends of the bearing pins 10^a and 11^a, thereby serving to resiliently oppose movements of the levers 4 and 5 by centrifugal action.

90

The stationary parts of the device are carried by a base or bracket 17 that is suitably secured to the frame or other stationary part of the magneto, generator or engine, and is provided with a cylindrical sleeve portion 18 surrounding the levers 4 and 5, the lower portion of the said sleeve being omitted or cut away for a distance of approximately 90 degrees. The sleeve 18 serves as a bearing for another sleeve 19 that closely fits the 100 same and the lower portion of which is also omitted or cut away, the said sleeve constituting a part of, and a support for, a shell or frame 20 having lugs 21 for the attach-

ment of means whereby the same may be rotated manually by the driver or operator.

A lever 22 is mounted within the frame 20 and is provided at one end with a block 23, of fiber or other suitable material, which projects through the cut away portions of the sleeves 18 and 19 into the path of the rollers 10 and 11. The face 24 of the block 23, that is adapted to be engaged by the rollers, has a curvature that is slightly eccentric to the circular path of rotation of the rollers 10 and 11.

The lever 22 is provided, at an intermediate portion, with an integral curved portion 22^a to be received by a depression 25 in a member 26 and which forms a fulcrum for the lever 22. The member 26, which is supported by and insulated from the frame 20, is provided with an arm 27 having a bent portion 28. A coil spring 29 bears at one end against the bent portion 28 and, at the other end, upon the opposite end of the lever 22. The lever 22, which may be pressed from light sheet metal, is turned down at the edges to form a rigid, channel-like member.

A blade spring 30, that is weaker than the spring 29, is attached at one end to the member 26. At the other end, it bears a contact piece 31 which coacts with a stationary contact piece 32. The lever 22 is provided with bent arms or hooks 33 which engage the spring 30 upon its lower side to form a lost motion connection to the same.

The spring 30, when not engaged by the hooks 33, is adapted to press the contact piece 31 against the contact piece 32. The contact piece 31 is electrically connected through the spring 30 and the member 26, to a binding post 34 that is insulated from the shell or frame 20. The contact piece 32 is connected through a conductor 35 to a similar binding post 36.

The lever 22 is normally held in its upward position against a stop 37, the engaging surface of which is composed of insulating material. In this position of the lever, the hooks 33 hold the spring 29 upwardly to separate the contact pieces 31 and 32.

In the operation of the device, the weighted ends of the levers 4 and 5 are moved outwardly by centrifugal force, against the action of the springs 12, in proportion to the speed at which they are revolved, the rollers 10 and 11 being thus moved around the pins 2 and 3, respectively, as centers. The relation of the parts is such that, as the arms 4 and 5 are actuated by centrifugal force, the rollers 10 and 11 are advanced from their initial or normal positions in the direction of revolution, being thus caused to engage the eccentrically curved face 24 of the block 23 sooner with respect to the corresponding positions of the

engine pistons for the higher engine speeds than for the lower. The result is that the spark occurs in the engine cylinders sooner with respect to the positions of the pistons than would otherwise be the case. Furthermore, because of the pivoting of the levers 4 and 5 eccentrically with respect to their axis of revolution and of the peculiar relations of the parts, the rollers 10 and 11 are not only advanced by centrifugal action upon the levers, but they are also moved radially outward as the speed of the engine increases. Then, since the face 24 of the block 23 that is adapted to be engaged by the rollers 10 and 11 is eccentrically curved, the rollers 10 and 11 will not only engage the said face sooner with the higher speeds, but will also engage it during greater portions of their angular movements at the higher speeds. The arrangement is such that, as the speed of the engine increases, the angular distance of engagement between the rollers and the lever will correspondingly increase, thereby maintaining the periods of engagement of the contact members of the interrupter substantially uniform with changes of speed. The importance of this feature will be appreciated when it is understood that the interrupter contact members should engage a certain period of time for the most effective production of the spark, and that, if this period is exceeded, more than the necessary amount of current will be utilized, whereas, if it is diminished, the spark is likely to be less effective and reliable.

With the present device, the period of engagement of the interrupter contact members may be adjusted for the most effective operation at slow speeds, and this period will be automatically maintained substantially uniform at all engine speeds, by reason of the construction and operation of the device as above set forth. In the use of the device, a manual adjustment will preferably be made, once for all, for the most desirable and effective advance or lead of the spark, permitting the device to thereafter operate automatically to maintain a suitable advance, though, if desired, the adjustment of the frame 20 may also be under the control of the operator or driver. Owing to the relatively rapid movement of the rollers 10 and 11, the latter permit the block 23 and the lever 22 to move freely upwardly under the force of the spring 29 at varying engine speeds, and the separation of the contact members takes place with uniform motion.

An advantage of the arrangement provided by my invention is that the lever 22 does not carry current. This construction avoids moving contact surfaces or shunt circuits that are usually required in the devices of this character.

A modification of my invention is shown

in Fig. 3 in which like numerals designate corresponding parts. The rotatable portion comprises a shaft 1 upon which is fixed a cam disk 38 having concentrically curved surfaces 39 and flat faces 40. A block 41, that is mounted upon a lever 42, projects into the path of the curved surfaces 39. The lever 42 is provided, at an intermediate portion, with a curved member 43 which has a bearing in a block 44. A contact piece 45 is mounted upon and connected to the lever 42 and coacts with a stationary contact piece 46 that is mounted upon a conducting arm 47. A coil spring 29, which bears at one end against a bent portion 48 of a member 49, normally holds the lever in position with the contact pieces in engagement. Binding posts 34 and 36 connect the contact pieces 45 and 46, respectively, to the primary circuit of an ignition system (not shown). The lever 42 is a channel-like structure similar to the lever 22 of Fig. 2.

In the operation of the interrupter of Fig. 3, the primary circuit is normally closed by the contact pieces 45 and 46. The contact pieces 45 and 46 are separated twice during each revolution of the cam disk by the curved faces 39.

I claim as my invention:

1. In an interrupter, the combination with a stationary contact member, of a lever having a substantially semi-circular bearing member, integral therewith, a contact member controlled by said lever to coact with said stationary contact member, means for actuating said lever, and resilient means for normally retaining said lever in one position.

2. In an interrupter, the combination with a stationary contact member, of an oscillatable lever of substantially channel-shape in cross-section and having a substantially semi-circular bearing member integral therewith, a contact member controlled by said lever to coact with said stationary contact member, means for actuating said lever, and means for yieldingly maintaining said lever in one position.

3. In an interrupter, the combination with a plurality of relatively movable contact members, of a lever having a lost-motion connection to one of said contact members, and resilient means for actuating one of said contact members in opposite directions.

4. In an interrupter, the combination with a plurality of relatively movable contact members, of a spring which carries one of said contact members, a lever of substantially channel shape in cross section and having a hook to form a lost motion connection to said spring, means for actuating said lever, and means for yieldingly holding said lever in one position.

5. In an interrupter, the combination with a plurality of relatively movable contact

members, of a spring having a stationary support and which carries one of said contact members, a lever having a lost-motion connection to said spring, and a second spring for normally retaining said lever in one position.

6. In an interrupter, the combination with a plurality of relatively movable contact members, of a spring having a stationary support and which carries one of said contact members, a lever which has a lost-motion connection to said spring, and means for normally holding said lever in position with said spring under tension.

7. In an interrupter, the combination with a plurality of relatively movable contact members, of a spring having a stationary support and which carries one of said contact members and tends to press said contact members together, a lever having a lost-motion connection to said spring, a second spring for holding said lever in one position with the other spring under tension, and means for actuating the lever to decrease the tension of the other spring.

8. In an interrupter, the combination with a plurality of coacting contact members, a relatively weak spring carrying one of said contact members and tending to press said contact members together, a lever having a lost-motion connection to said spring, and a relatively strong spring for holding said lever in one position to oppose the weak spring and thereby separate said contact members.

9. In an interrupter, the combination with a plurality of relatively movable contact members, of a spring having a stationary support and carrying one of said contact members, a lever having a lost-motion connection to said spring, and a spring normally holding said lever in position to separate said contact members.

10. In an interrupter, the combination with a pair of relatively movable contact members, of a lever of substantially channel-shape in cross-section for controlling one of said contact members, and means for periodically actuating said lever.

11. In an interrupter, the combination with a pair of relatively movable contact members, and a spring for carrying one of said contact members, of a lever connected to said spring, means for actuating said lever in opposite directions to respectively permit the engagement of said contact members and to disengage said contact members against the force of said spring.

12. In an interrupter, the combination with a pair of relatively movable contact members, and a fixedly mounted spring for carrying one of said contact members, of a lever connected to said spring, means for actuating said lever in opposite directions to respectively permit said spring to effect

the engagement of said contact members and to disengage said contact members and thereby increase the tension of said spring.

13. In an interrupter, the combination
5 with a pair of coacting contact members, of
means for controlling one of said contact
members comprising a lever having a sub-
stantially semi-circular bearing member.

In testimony whereof, I have hereunto
subscribed my name this 2nd day of August 10
1913.

THEODORE ABTMEYER.
